EDWARD W. STIFEL, OF WHEELING, WEST VIRGINIA, ASSIGNOR TO J. L. STIFEL & SONS, OF WHEELING, WEST VIRGINIA, A FIRM.

PRINTED TEXTILE FABRIC.

1,118,516.

Specification of Letters Patent. Patented Nov. 24, 1914.

Application filed February 10, 1914. Serial No. 817,817.

To all whom it may concern:

Be it known that I, EDWARD W. STIFEL, a citizen of the United States of America, and resident of Wheeling, county of Ohio, and State of West Virginia, have invented certain new and useful Improvements in Printed Textile Fabrics, of which the following is a specification.

This invention relates broadly to printed textile fabrics, and it has for its primary object to provide a textile fabric having printed thereon figures or designs which simulate in appearance like figures or designs formed by weaving in the fabric threads of a color or shade different from that of the fabric body.

A further object is to provide a woven textile fabric which has printed thereon in a color contrasting with that of the fabric body stripes or figures composed of fine broken lines or dots which present the appearance of scattered threads of said contrasting color interwoven in the fabric.

With these and other objects in view, the invention resides in the features which will hereinafter be fully described, reference being had to the accompanying drawings, forming a part of this specification, in which—

Figure 1 is a plan view of a highly magnified portion of a printed fabric embodying my invention; Fig. 2 is a section on the line 2—2, Fig. 1; and Fig. 3 is a view similar to Fig. 1, unmagnified, the twill on the surface of the fabric not being shown.

In said drawings, like designating characters distinguish like parts throughout the several views.

The material employed is a drilling, denim or other fabric wherein, in weaving, the weft threads are passed over one and under two or more warp threads, producing a diagonally ribbed or twilled surface.

To produce a design or figure, as the stripes A, on the fabric B, which latter is preferably of solid color so that said design or figure presents the appearance of having been formed by weaving in the fabric threads of a color contrasting with the solid color, a series of fine lines C of said contrasting color is applied to the twilled surface, said lines being disposed parallel to each other and at an angle, or diagonal, to the twills D. Printing rolls of a common type are employed for applying said con-

trasting color to the fabric. Said rolls have broken printing lines provided thereon, said lines being composed of short lines or dots of irregular length. When applied to the fabric, said printing lines lightly contact with the twilled surface, engaging for the most part only the tops or elevated surfaces of the twills, leaving the grooves or valleys E between said twills untouched except at occasional points. Thus, short broken printed lines or dots a of the contrasting color are presented on the surface of the fabric, said broken lines or dots being located mainly upon the elevated surfaces of the twills, as shown in Figs. 1 and 2, although there may be found an occasional continuous line, as a', extending across two or more twills and the intervening valleys E.

Examined under a microscope or magnifying glass, the printed lines present the rough and ragged appearance depicted in Fig. 1, but, viewed with the naked eye, the lines appear as shown in Fig. 3 and simulate quite closely scattered threads of the contrasting color interwoven with the threads of the solid color fabric. This simulation can only be obtained by having the printing lines of the printing roll apply the printed lines in a direction transverse, or diagonal, to the twill of the fabric so that the last mentioned lines will be broken. A disposition of the lines on the fabric parallel, or substantially parallel, to the twill results in the production of a mottled or wavy effect instead of the weave-simulating effect sought; this being due to the fact that the printing lines of the printing rolls quite as often fall in the grooves or valleys E as upon the twills of the fabric, in which position the printing material, if applied at all, is applied too lightly. In other words, when the printing lines are applied parallel to the twill it is impossible to have them fall upon the top surface of the twills with such regularity as to produce the desired result. For a like reason, the printing lines are also disposed across, or diagonal with respect to, the twist threads of the fabric.

What is claimed is—

1. As an article of manufacture, a textile fabric having a twilled surface and having fine broken lines of a contrasting color printed on said surface, said lines being disposed in a direction diagonal both with respect to the twills and to the twist threads.

2. As an article of manufacture, a textile fabric having a twilled surface and having fine broken lines of a contrasting color applied to the twills by printing, said lines extending in a direction across said twills and the twist threads.
3. A textile fabric having a twilled surface and having designs or figures printed thereon in simulation of woven designs or figures, said designs or figures being formed of fine broken lines applied across the elevated portions of the twills and across the twist threads.
4. A textile fabric having a twilled surface and having designs or figures printed thereon in simulation of woven designs or figures, said designs or figures being formed of a series of fine broken parallel lines disposed transverse both with respect to the
- twills, and to the twist threads which lines are further broken by the valleys intervening between the twills.
5. A textile fabric having a twilled surface and having a plurality of broken printed lines in a color contrasting with that of the fabric body disposed upon the elevated portions of the twills to simulate scattered threads of the contrasting color interwoven in the fabric, said lines extending in a direction transverse both with respect to the twills and to the twist threads and arranged to form a figure of predetermined design.

In testimony whereof, I affix my signature in presence of two subscribing witnesses.

EDWARD W. STIFEL.
